No. 626,266.

Patented June 6, 1899.

C. BOMBERGER.
COVER FOR LOCKS FOR STREET LETTER BOXES.

(Application filed Mar. 10, 1899.)

(No Model.)

UNITED STATES PATENT OFFICE.

CYRUS BOMBERGER, OF CANTON, OHIO.

COVER FOR LOCKS FOR STREET LETTER-BOXES.

SPECIFICATION forming part of Letters Patent No. 626,266, dated June 6, 1899.

Application filed March 10, 1899. Serial No. 708,545. (No model.)

To all whom it may concern:

Be it known that I, CYRUS BOMBERGER, a citizen of the United States, residing at Canton, in the county of Stark and State of Ohio, have invented certain new and useful Improvements in Covers for Locks for Street Letter-Boxes; and I do hereby declare that the following is a full, clear, and exact description of the same, reference being had to the annexed drawings, making a part of this specification, and to the figures of reference marked thereon, in which—

Figure 1 is a perspective view showing my invention applied to use. Fig. 2 is a detached view of the catch. Fig. 3 is a detached view of the hinge connecting-plate. Fig. 4 is a view showing a portion of a letter-box and illustrating the same open. Fig. 5 is a detached view of the lock-protecting plate. Fig. 6 is a transverse section of the lock-protecting plate. Fig. 7 is a view of a portion of a letter-box, showing the same closed and the lock-protecting plate open.

The present invention has relation to covers for locks for street letter-boxes, and has particular reference to the protecting of the lock and hasp from snow and ice; and it consists in the different parts and combination of parts, hereinafter described, and particularly pointed out in the claim.

Similar numerals represent corresponding parts in all the figures of the drawings.

In the accompanying drawings, 1 represents the letter-box, which may be of the form shown, or it may be of any other desired form, inasmuch as the box within itself forms no particular part of the present invention, except that a box must necessarily be used to carry out the object and purpose of the invention.

The door 2 is hinged in the ordinary manner and is of the ordinary construction, reference being had to properly connecting my improvement thereto. The lock-protecting plate 3 is preferably of the form shown, and, as shown, it consists of an elongated cup-shaped plate formed of such a size that it will properly cover and protect the lock 4 and the hasp 5. The lock-plate 3 is provided with the arm or extension 4, which is preferably

located at the point shown in the drawings, and is for the purpose of engaging the catch 5, which catch may be connected to the box, as shown in Fig. 1. Said catch is formed or made at the time the box proper is constructed. 55 The catch 6 is substantially the same as the catch 5, except that it is provided with the connecting-plate 7, which connecting-plate is riveted or otherwise connected to the mail-box proper. This construction is necessary 60 when my improvement is to be connected to mail-boxes now in use.

In applying my invention to mail-boxes already in use the connecting-plate 8 is provided, which connecting-plate is provided 65 with the ears 9, said ears being for the purpose of forming one side of the hinge for the plate 3. The plate 8 is to be riveted to the door 2 and the plate 3 connected thereto by means of the ears 10 and a suitable connecting-pin. The connecting-pin 9 is formed of such a length that it will properly connect the different ears forming the hinge together, and is so formed for the purpose of providing a means for removing the protecting-plate 3 75 from the box proper when it is not to be removed.

It will be understood that during the summer season the protecting-plate can be entirely removed from the box; but in the winter season, when ice forms, the protecting-plate is to be applied.

When the lock and hasp-hinge are exposed to severe weather, ice forms in the lock, which prevents the opening of the lock, and by the 85 formation of ice upon the hasp-hinge its hinge and hasp are liable to become broken. It will be understood that by my peculiar arrangement the lock and its different parts will be protected.

For the purpose of allowing the plate to come snugly against the door the notches 11 are formed, which notches are for the purpose of allowing the water-table 12 to be received into the notches.

For the purpose of preventing water from finding its way between the dished plate 3 and the outer face of the door 2, or that portion of the door covered by said dished plate, the water-table 13 is provided, which water-table 100

is located directly above the top or upper end of the plate 3.

Having fully described my invention, what I claim as new, and desire to secure by Letters Patent, is—

The combination of a street letter-box provided with a door, the lock-protecting plate 3 hinged to the door of the letter-box and provided with the arm or extension 4, a catch to engage said extension, notches formed in the

plate to receive the water-table, all arranged, substantially as and for the purpose specified.

In testimony that I claim the above I have hereunto subscribed my name in the presence of two witnesses.

CYRUS BOMBERGER.
